*Primary Examiner—Stacia Cadmus***CLAIM**

The ornamental design for a sun visor extension, as shown and described.

DESCRIPTION

FIG. 1 is a front elevational view of the sun visor extension of the present invention;

FIG. 2 is a back elevational view of the sun visor extension of FIG. 1;

FIG. 3 is a left side elevational view of the sun visor extension of FIG. 1;

FIG. 4 is a right side elevational view of the sun visor extension of FIG. 1;

FIG. 5 is a top plan view of the sun visor extension of FIG. 1; and,

FIG. 6 is a bottom plan view of the sun visor extension of FIG. 1.

The broken lines showing an automotive sun visor in FIGS. 5 and 6 are for illustrative purposes only and form no part of the claimed design.
